INSULATOR SUPPORT AND COUPLING
METHOD

Donnan E. Basler, Jackson, Mich., Harold W. Kelley, Port St. Joe, Fla., and Norris Whitney Matthews, Caldwell, Ohio

Application August 30, 1941, Serial No. 408,928

1 Claim. (Cl. 174—158)

(Granted under the act of March 3, 1883, as
amended April 30, 1928; 370 O. G. 757)

The invention described herein may be manufactured and used by or for the Government of the United States for governmental purposes without the payment to us of any royalty thereon in accordance with the provisions of the act of April 30, 1928 (Ch. 460, 45 St. L. 467).

This invention pertains to improvements in insulators for electric transmission and distribution lines and more particularly to means for mounting pin-type insulators having a conductor saddle.

In constructing electric transmission and distribution lines using pin-type insulators which are conventionally threaded and screwed onto a supporting member difficulty has been experienced in aligning the axis of the conductor saddle of the insulator with the conductor and retaining such alignment when once properly mounted.

The present invention aims to insure axial alignment of the conductor saddle, in the mounting thereof, with the conductor by the provision of positive positioning means and further aims to insure such positioning by the provision of means preventing disalignment of the saddle axis by rotation of the insulator with respect to its support.

A further aim of the invention is to provide means for preventing the accidental or unintentional lifting of the insulator from its support, such as by undue tension on a conductor secured within the saddle of the insulator.

A further object of the invention is to provide an improved insulator-supporting member adapted to cooperate with the insulator for the accomplishment of the aforesaid objects.

The foregoing and other objects of the invention will become apparent from a reading of the following specification and appended claim. Certain embodiments having the characteristics of our invention and by which the same may be practiced are illustrated in the accompanying drawing in which,

Figure 1 is a view in side elevation of an embodiment of our invention, a portion of the insulator support being broken away to illustrate the formations and cooperative relationship of elements;

Figure 2, an elevation of a slightly modified embodiment of our invention in assembled form;

Figure 3, a view in perspective of unassembled elements of the Figure 1 embodiment;

Figure 4, a view in perspective of the unassembled elements of an adaptation of our invention; and

Figure 5, an elevational view of the Figure 4

embodiment modified to the extent of eliminating the vertical locking means.

Broadly, the invention resides in modifying the shank of conventional insulators of the type identified and correspondingly modifying the insulator-engaging end, or portion, of the insulator support to provide a non-rotative relationship between the respective members when mounted; to provide a clamping engagement by the support with respect to the insulator; to provide positive and restricted positioning of the axis of the conductor saddle of the insulator; and if desired to provide means preventing axial movement of the insulator with respect to its support.

According to our invention the foregoing aims and objects are accomplished by providing an insulator 10 with a mounting shank 11 which is non-circular, as shown in Figures 1-3, and providing an insulator support 12, as shown in the latter figures, which is so formed as to non-rotatively receive the insulator mounting shank 11 only in a manner whereby the axis of the conductor saddle 13 of the insulator 10 is in proper predetermined alignment with the conductor to be carried therein.

The foregoing aims and objects may also be accomplished according to our invention by providing a circular insulator mounting shank 14, as shown in Figures 4 and 5, with a key 15 and providing an insulator support 16, shown in the latter figures, which is so formed as to non-rotatively receive the insulator mounting shank 14 in a manner whereby the axis of saddle 13 of the insulator is in proper predetermined alignment.

In the embodiment of Figures 1 and 3 the shank is of rectangular formation and disposed so as to have its greatest length correspond with the axis of the saddle 13. The cooperative insulator support 12 for the embodiment of Figures 1 and 3 is provided with a seat-portion 17 which is in turn provided with a socket 18 of configuration corresponding with that of the shank 11. In order to seat the insulator upon the seat-portion 17 of the support the insulator shank 11 must first be brought into registry with the socket 18, thereby positively bringing the axis of the insulator saddle 13 into predetermined alignment. In order to secure the insulator in seated relationship with the support 12 means are provided for clamping the insulator shank 11 between the walls of the socket 18. Suitable means for this purpose may comprise a bolt 19 extending through the forward end portions 20 of the seat-portion 17 whereby the end portions 20 may

be drawn into clamping relationship with the walls of the insulator shank 11.

In the embodiment of Figures 1 and 3 the shank 11 may be inserted into the socket 18 of the support in a vertical direction or, by the removal of the bolt 19, longitudinally into the opening. In this respect the embodiment of Figure 2 differs from that of Figures 1 and 3 by the provision of shoulders 21 adapted to pass beneath the seat-portion 17 and serve as means for preventing the vertical lifting of the insulator from its support. In mounting this modified embodiment the bolt 19 must first be removed and the shank 11 passed horizontally into the socket 18. The bolt 19, Figure 2 embodiment, when once installed serves as means for locking the insulator within the socket against longitudinal movement and the shoulders 21 as means for preventing the vertical movement of the insulator. By this arrangement there need not be a clamping action as required in the Figures 1 and 3 embodiment to lock the insulator to the support.

In the embodiments of Figures 4 and 5 the circular insulator mounting shank 14 is provided with a flange or key 15 and the cooperating insulator support 16 is provided with a socket 22 having a gap 23 in one wall thereof and a bolt 24 through a pair of ears 25 extending from opposite sides of the gap 23. The socket 22 is of a size and configuration as will receive the shank 14 and the gap 23 such as will permit the key 15 to pass therewith. The positioning of the key 15 and the gap 23 is such as will predeterminately fix the direction of the axis of the insulator saddle 13 with respect to the support when the members are cooperatively assembled. When assembled a tightening of the bolt 24 will bring about a clamping of the insulator shank 14 within the socket 22. By this arrangement the key 15 and slot 23 not alone serve to locate the proper saddle axis in alignment with a conductor, but also serve to insure against rotary displacement of the insulator with respect to the support. The width of the gap 23 may be such, but not necessarily so, as will afford a clamping action upon the key 15 as well as upon the insulator shank 14 when the bolt 24 is tightened. For simplicity in construction the key 15 may be an integrally formed por-

tion of the insulator, but other manners of formation or manners of providing a shank with an alignment-finder key may be equally suitable and within the scope of the invention.

5 To insure against unintentional lifting of the insulator shank 14 from the support socket 22, the walls of the socket-forming member may be drilled through as at 26 and 27, Figure 4, and the shank 14 of the insulator similarly notched as at 28, Figure 4, to cooperatively receive a pin 29 which, when installed, will serve to interlock the respective elements against separation even in the event that the insulator shank is not clamped within the socket 22 of the support.

15 Except for the features described, the insulator supports may otherwise be of any standard or designed types, such as are known in commerce as "pole-top pins," "side brackets," "cross-arm pins" or "clamps," etc., which are conventionally provided with a threaded end portion for engagement with a threaded shank of conventional insulators.

25 Except as limited by the scope of the appended claim, it is to be understood that applicants' invention is not to be construed as limited to the specific embodiments illustrated for the purpose of describing the invention and that the shape of the insulator shank and the cooperating socket of the support may be triangular, quadrangular, 30 or any polygon, or any other shape which may render the same non-rotative with respect to each other when assembled.

35 Having described our invention, what we claim is:

40 An insulator mounting means comprising an insulator having a mounting shank provided with an integral aligning key and a transverse pin-receiving recess, an insulator support provided with a socket for said shank and key and a hole aligning with said recess of the insulator shank, and means adapted to be secured in said aligned pin-receiving recess and socket opening for detachably locking said insulator in said socket.
